UNITED STATES PATENT OFFICE.

AUSTIN W. BARBER, OF EVERETT, WASHINGTON.

IRONING-BOARD.

1,134,662.

Specification of Letters Patent.

Patented Apr. 6, 1915.

Application filed February 13, 1913. Serial No. 748,236.

To all whom it may concern:

Be it known that I, AUSTIN W. BARBER, a citizen of the United States, residing at Everett, in the county of Snohomish and State of Washington, have invented new and useful Improvements in Ironing-Boards, of which the following is a specification.

This invention relates to improvements in ironing boards and more particularly to a vertically adjustable ironing board and one which may be folded in a cabinet and put out of the way when not in use.

An object of the invention is to provide an ironing board cabinet of simple, durable and inexpensive construction in which an ironing board may be supported and contained in such a manner as to be concealed from view, and when it is desired to use the ironing board it may be readily, quickly and easily swung to a horizontal position and there firmly and securely held as required in use.

Another object of this invention is to provide an ironing board so constructed and proportioned that it balances well and to mount this board upon connections with the cabinet, heretofore mentioned, in such a manner that only a very little exertion, such as a slight push upon the outer end, will be necessary to cause the board to assume its inoperative position within the cabinet and to accomplish this self-balancing feature without the aid of springs, weights or the like.

A still further object of this invention is the provision of an ironing board of this nature which can be manufactured at a minimum cost, one which will afford sufficient strength, stability and durability for all purposes to which it will be ordinarily subjected and one which will be convenient in use and which when not in use may be folded in its cabinet thus economizing much space.

Among the many other objects of this invention is the provision of supporting devices for the ironing board which may be readily, quickly, and easily adjusted vertically so that the ironing board will be supported in a horizontal position at various elevations to suit the desire of the one using

the board and to provide a novel and convenient manner of stretching the cloth and holding the same upon the ironing board.

With the foregoing and other objects in view, this invention consists of such novel features of construction, combination and arrangement of parts as will be hereinafter more fully described, illustrated in the accompanying drawings and claimed.

In describing the invention in detail, reference will be had to the accompanying drawings wherein like characters of reference designate like or corresponding parts throughout the several views, and in which:

Figure 1 is a sectional view through the cabinet showing the ironing board and the supporting means therefor in elevation and showing the ironing board in a horizontal or operative position. Fig. 2 is a top plan view of the ironing board showing the cabinet in section. Fig. 3 is a fragmentary sectional view through the cabinet showing the ironing board folded therein and the door of the cabinet closed. Fig. 4 is a detail view showing the manner of mounting the bracing means in the cabinet. Fig. 5 is a perspective view of the bracket which is secured to the under side of the ironing board and to which the bracing means is attached. Fig. 6 is a detail fragmentary view of the outer end of the ironing board showing the means for securing a cloth thereon, and Fig. 7 is a detail plan view of the under side of the outer end of the ironing board showing parts in section and also showing the manner of attaching a cloth to the board.

In referring to the drawings by numeral, 1 designates a cabinet which may be of any ordinary construction and has a door 2 hingedly connected thereto. In Fig. 1 of the drawings the cabinet 1 is shown seated in a recess of the wall of a room but it is to be understood that this cabinet is so constructed that it may be placed either in a recess in the room or in any desired position in or about the room. Mounted within the cabinet and secured to each side thereof is a metallic plate 3 which is provided with an elongated slot 4. Projecting laterally from the upper end of the slot 4 is a series of

smaller slots 5. The lower end of the plate 3 is provided with a series of openings 6 which have the reduced angled ends 7 of the bracing member 8 mounted in a pair of them. The bracing member 8 is formed of a single piece of stout metal wire and is bent substantially U-shaped having the connected end normally mounted in the brackets 9 which are secured to the under surface of the ironing board 10 as is clearly shown in Figs. 1 and 2 of the drawings. The ends 7 of the bracing member 8 are bent outwardly and reduced as is clearly shown in Fig. 4 to enable them to be easily inserted into the openings 6 of the plate 3. The inner end 11 of the ironing board 10 has a rod 12 mounted therein, the ends 13 of which project a short distance beyond the sides of the ironing board 10 and are seated in a pair of lateral slots 5 of the plates 3. The series of transverse slots 5 and the series of openings 6 in the plates 3 form a means for vertically adjusting the ironing board 10 to suit the convenience of the person using the same.

The bracket 9 has projecting downwardly from one side thereof an extension 15 which is provided with a lateral slot 16. Slot 16 has its inner wall curved to form a bearing for the connected end of the U-shaped bracing member 8 and is open at one end of the bracket so that the member 8 may be easily mounted therein. The slot 16 further facilitates the folding of the ironing board into the cabinet, in that it allows limited free movement of the U-shaped brace 8, thus preventing binding between the same and the bracket 9 during the pivotal movement of the ironing board. When a slight push is administered to the end 17 of the ironing board 10 the ends 13 of the rod 12 will be pushed out of transverse recesses 5 and into the vertical recesses 4 of the plates 3 and will pass downwardly therein thus allowing the ironing board to assume the position that is shown in Fig. 3 of the drawings, when it will be folded in the cabinet 1 and out of the way.

The ironing board 10 is provided with a projection 20 which is formed upon the under surface thereof and which while being of somewhat the same shape as the main body portion of the ironing board is slightly smaller and has a groove 21 extending the entire distance therearound. Placed over the ironing board 10 is a cloth 22. This cloth 22 is folded under and about the projection 20 as is clearly shown in Figs. 6 and 7 of the drawings and is held securely in place by means of the wire 23 which is seated in the recess 21 and which has its ends connected to a thumb screw 24 which is mounted in the ironing board 10.

By turning the thumb screw 24 the wire 23 is either tightened or loosened about the

projection 20 and either securely holds the cloth 22 in place upon the ironing board 10 or permits the removal of the same from the ironing board.

From the foregoing description and the drawings, it will be clearly seen that all of the objects hereinbefore mentioned are carried out to the fullest extent in that, the ironing board can be easily and quickly adjusted vertically or folded within the cabinet 1 where it will be out of the way of any one working in the room in which it is placed.

In practical fields, certain minor features of construction and arrangement of parts may require alterations to which the patentee is entitled provided such alterations are comprehended within the scope of what is claimed.

What is claimed is:—

1. In an ironing board the combination with a cabinet having plates mounted therein provided with vertical slots and lateral slots communicant therewith, of an ironing board having means mounted thereon for adjustable engagement with said slots, a U-shaped bracing member having its vertex removably connected to said ironing board and its ends detachably connected to said metallic plates, and means provided in said plates for allowing vertical adjustment of said brace.

2. In an ironing board, the combination, with a cabinet having metallic plates mounted upon the interior of its sides, said plates provided with vertical slots and lateral slots communicating with said vertical slots, of an ironing board having pins mounted in the sides of one end thereof, said pins being adjustably seated in said slots for retaining said ironing board in adjusted position, a U-shaped bracing member having its vertex removably connected to the under surface of said ironing board and its free ends connected to said metallic plates, said free ends being vertically adjustable, by means of a plurality of openings formed in said plate for varying the horizontal elevation of said ironing board.

3. In an ironing board the combination with a cabinet having metallic plates mounted upon the interior of its sides, said plates being provided with vertical slots and lateral slots communicant with said vertical slots adjacent the upper end thereof, of an ironing board having pins mounted in the sides of one end thereof, said pins being adjustably seated within said slots for retaining said ironing board in an adjusted position, a bracket member secured to the under side of said ironing board and having an extension formed thereon projecting downwardly from one side thereof, said projection being provided with a lateral slot, a

U-shaped bracing member having its vertex removably mounted within said lateral slot formed in said bracket and its free ends connected to said metallic plates, said ends being vertically adjustable by means of a plurality of openings formed in said plate adjacent the lower extremity thereof for vary-

ing the horizontal elevation of said ironing board.

AUSTIN W. BARBER.
